UNITED STATES PATENT OFFICE.

GUY MORGAN, OF MIDDLETOWN, OHIO.

FORM FOR CONCRETE TOPS FOR CISTERNS, &c.

1,127,070.

Specification of Letters Patent.

Patented Feb. 2, 1915.

Application filed October 16, 1913. Serial No. 795,454.

To all whom it may concern:

Be it known that I, GUY MORGAN, a citizen of the United States, residing in Middletown, Butler county, Ohio, have invented 5 certain new and useful Improvements in Forms for Concrete Tops for Cisterns, &c., of which the following is a specification.

In the building of cisterns, sewer-chambers, etc., it is common to build the walls of 10 brick or to mold them of concrete around suitable forms, and then to form the roof by brick arching or by concrete molding. My present invention does not concern itself 15 with the wall-work of such structures but limits itself to a peculiar construction of form to be employed in molding the concrete roof.

My invention will be readily understood 20 from the following description, taken in connection with the accompanying drawing in which:—

Figure 1, is a diametrical vertical section of a cistern, or the like, having applied to 25 it my improved top form ready for the molding of the concrete roof; Fig. 2, a plan of one of the form-segments; and Fig. 3, a vertical transverse section of one of the form-segments, in the plane indicated by the dotted line in Fig. 2.

30 A diversity of scales is employed in the drawing.

In the drawing:—1, indicates the wall of the cistern or other chamber which is to be provided with a concrete roof; 2, the earth surrounding the wall; 3, sheet-metal segments of such dimensions as to extend from the wall to the central opening in the roof, and of such width as to be withdrawable through the central opening when the roof 40 is completed; 4, an angle-iron secured to and along one edge of each segment and projecting sidewise therefrom; 5, a gage secured to the outer end of each angle-iron and adapted to engage the inner surface of the wall and position the angle-iron and its attached segment in the radial direction; 6, a gaging claw at the outer end of each angle-iron and adapted to rest upon the wall and position the outer ends of the angle-irons vertical; 7, a clamp-piece adapted to engage under the inner ends of the angle-irons; 8, the usual top-ring employed in margining the opening in the top of the cistern, this top-ring engaging over the inner ends of the segments; 50 9, a clamp-bar engaging below the clamp- piece 7; 10, a clamp-bar engaging over top-ring 8; 11, a clamp-bolt extending through clamp-bars 9 and 10 and serving to draw clamp-piece 7 and top-ring 8 against the angle-irons so as to clamp the angle-irons between them; 12, a nut upon the upper end of the clamp-bolt; 13, the radial margins of the segments at the sides of the segments opposite the sides which are provided with angle-irons; 14, a groove extending along between 60 the angle-irons and the edges of the segments which are attached to the angle-irons; and 15, a downwardly projecting fold radially disposed in each segment and serving to give transverse flexibility to the segments, 65 the fold opening more or less, with a hinge-like action and permitting the metal at each side of the fold to take varying angular relationships to each other.

It is, of course, to be understood that the 70 sheet - metal form - parts and their angle-irons are to be of a form and size suited to the chamber whose roof is to be molded. It has been thought best to illustrate the device as adapted for molding the roof of a cis- 80 tern with a circular wall to have a frusto-conical roof. In using the device in forming the roof of a circular cistern, the segments are arranged in circumferential order with the gages 5 and 6 engaging the wall, the 85 groove 14 at each angle-iron being engaged by the opposite edge of the following segment. Fold 15 gives to each segment a transverse flexibility permitting it to more readily conform itself to the frusto-conical 90 form and to permit the edges 13 to readily engage within the groove 14. When the segments have been thus associated a fairly strong mold-structure has been produced. Top-ring 8 is now to be positioned and the 95 clamping parts applied in an obvious manner. The concrete is now to be applied and when it has properly set then the clamping-work is removed and withdrawn through the top-ring which remains in the concrete 100 work as a part of the roof structure. One of the segments may now be pulled loose from under the roof and withdrawn through the top-ring, after which the remaining segments may be withdrawn in succession. It 105 has been found in practice that the device is very efficient and that it may be placed in working position and withdrawn therefrom by one man, and that no interior supporting work is necessary.

I claim:

1. A form for concrete chamber-tops comprising, angle-irons extending inwardly from the outer portion of the intended roof, a support for the inner ends of the angle irons, gages carried by the outer ends of the angle-irons and adapted to engage within and above the wall of the chamber over which the roof is to be erected, and sheet-metal members each having one edge secured to one of said angle-irons and having its other edge adapted to rest upon another one of the angle-irons, combined substantially as set forth.
- 15 2. A form for concrete chamber-tops comprising, angle-irons extending inwardly from the top of the walls, gages carried by the outer ends of the angle-irons and adapted to engage the inner surface and top of the wall of the chamber over which the roof is to be erected, sheet-metal members each having one edge secured to one of said angle-irons and having its other edge adapted to rest upon another one of the angle-irons, a top-ring resting upon the inner ends of the sheet-metal members and adapted to serve in margining the central opening in the molded roof, and clamping devices engaging over said top-ring and below the inner ends of the angle-irons, combined substantially as set forth.
- 20 3. A form for concrete chamber-tops comprising, angle-irons extending inwardly from the top of the walls, gages carried by the outer ends of the angle-irons and adapted to engage the inner surface and top of the wall of the chamber over which the roof is to be erected, sheet-metal members each having one edge secured to one of said angle-irons and having its other edge adapted to rest upon another one of the angle-irons, a top-ring resting upon the inner ends of the sheet-metal members and adapted to serve in margining the central opening in the molded roof, and clamping devices engaging over said top-ring and below the inner ends of the angle-irons, combined substantially as set forth.
- 25 4. A form for concrete chamber-tops comprising, angle-irons extending inwardly from the top of the walls, gages carried by the outer ends of the angle-irons and adapted to engage the inner surface and top of the wall of the chamber over which the roof is to be erected, sheet-metal members each having one edge secured to one of said angle-irons and having its other edge adapted to rest upon another one of the angle-irons, a top-ring resting upon the inner ends of the sheet-metal members and adapted to serve in margining the central opening in the molded roof, and clamping devices engaging over said top-ring and below the inner ends of the angle-irons, a cross-bar disposed over said top-ring, a ring engaging below the inner ends of the angle-irons, a cross-bar disposed below the last-mentioned ring, and a bolt engaging the two cross-bars, combined substantially as set forth.
- 30 5. A form for concrete chamber-tops comprising, a circumferential series of radially disposed angle-irons extending inwardly from the outer portion of the intended roof, gages carried by the outer ends of the angle-irons and adapted to engage within and above the wall of the chamber over which the roof is to be erected, sheet-metal members each having one edge secured to one of said angle-irons and having its other edge adapted to rest upon another one of the angle-irons and enter a groove formed between the angle-iron on which it rests and the edge of the sheet-metal member to which that angle-iron is attached, combined substantially as set forth.
- 35 6. A form for concrete chamber-tops comprising, segmental sheet-metal roof members adapted to extend inwardly from the wall of the chamber to be roofed, and downward folds extending from the inner to the outer ends of said members and adapted to give transverse flexibility to them, combined substantially as set forth.

GUY MORGAN.
